UNITED STATES PATENT OFFICE

HUBERT LANG, OF CHICAGO, ILLINOIS, ASSIGNOR TO GOSS PRINTING PRESS COMPANY,
A CORPORATION OF ILLINOIS

WEB ROLL SUPPORTING MECHANISM

Application filed April 22, 1929. Serial No. 357,097.

The invention relates to new and useful improvements in web roll supporting and handling mechanism and more especially to a web roll supporting and handling mechanism for use with printing presses or other web-using machines.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, construction, arrangements, combinations and improvements herein shown and described.

The accompanying drawings, referred to herein and constituting a part hereof, illustrate one embodiment of the invention, and together with the description, serve to explain the principles of the invention.

Of the drawings:

Figs. 1 and 1^a are in part elevations of a web roll supporting and handling mechanism embodying the invention, and impart sections taken on the lines 1—1 and 1^a—1^a respectively of Fig. 4;

Fig. 2 is an end view of the mechanism shown in Figs. 1 and 1^a;

Fig. 3 is a cross section of the web roll supporting mechanism taken on the line 3—3 of Fig. 1^a;

Fig. 4 is a section taken on the line 4—4 of Fig. 2;

Fig. 5 is a detail sectional view of one of the spindle mechanisms and taken on the line 5—5 of Fig. 1;

Fig. 6 is a detail of the spindle shown in Fig. 5, certain parts being broken away, and showing the spindle in retracted position;

Fig. 7 is a cross section taken on the line 7—7 of Fig. 6;

Fig. 8 is a detail of a portion of the mechanism for laterally moving the web roll supports, with certain parts broken away;

Fig. 9 is a section taken on the line 9—9 of Fig. 8;

Fig. 10 is a section taken on the line 10—10 of Fig. 8; and

Fig. 11 is a detail, corresponding to Fig. 8, but with the parts out of engagement so the supports may be moved independently of the moving means and with other parts broken away.

The invention is directed to novel and useful means for handling, alining, rotatably supporting, laterally registering web rolls of paper and other material and for effecting these functions with web rolls of various widths, the web being usually drawn off under tension and also usually at high and varying speeds by the web consuming machine. The invention is further directed to providing such a mechanism which is unusually adequate and efficient for performing all of those functions separately and conjointly, and without causing disturbance or necessity for adjustment of other of the mechanisms or means.

A further object of the present invention is to provide a web roll supporting mechanism which dispenses with and renders unnecessary the web roll supporting spindle or mandrel, heretofore used in connection with the web rolls, and thereby dispense with the necessity of fastening thereto the brake pulley, bringing the brake pulley into proper relation with the brake mechanism and later removing the brake mechanism and pulley when a new web roll is to be placed in running position. By my invention a web roll is quickly and positively positioned with respect to the mechanisms, is quickly and readily brought into lateral registration with the printing press cylinders or other web using machine, for web rolls of all widths, and is immediately in proper relation with the braking mechanism, and an exhausted roll is removed from the mechanism.

The invention in its entirety comprises means for supporting a fresh web roll which has no spindle but only an axial orifice or tube, and bringing it with certainty to an initial position with respect to the mechanism, and also means are provided for easily lifting the fresh web roll into registry with the supporting spindles. A pair of rotatable spindles are provided for receiving, and engaging in, the ends of the axial orifice of the

web roll after it has been moved into alignment with the spindles. At least one of the spindles is longitudinally movable to clamp the roll and spindles together. The carriers 5 for the spindles are movable toward and from each other, to accommodate rolls of web of various widths. The supports for these spindles are very accurately axially movable so as to readily and nicely bring the 10 web roll supported by them into transverse registry with the plates on a printing press or into like relation with any other kind of web-using machine with which the web roll supporting and handling mechanism is used. 15 Braking means are provided in connection with one of the spindles, to control the tension of the web drawn off from the web roll and to maintain the tension at the desired and necessary value for the particular conditions under which the printing press or 20 other web-using mechanism is operating. The removal of the core of an exhausted web roll is effected by a simple movement of one of the supporting spindles. 25 It will be understood that the foregoing general description and the following detailed description as well, are exemplary and explanatory of the invention but are not restrictive thereof. 30 Referring now in detail to the present preferred embodiment of the invention as illustrated by the accompanying drawings, the web roll supporting and handling mechanism, as a whole, is supported on a frame or 35 bed comprising a pair of spaced-apart longitudinally-extending frames 20 at each side of the mechanism, which frames are rigidly held in spaced-apart relation by end frames 22, at the ends of the mechanism, to which 40 the side frames are securely bolted.

For supporting the web roll engaging means, there is provided a pair of upwardly-extending supporting members or pedestals 23 and 24 supported on the base by engagement 45 with the side frames 20, and for increasing the rigidity of these supporting members 23 and 24, they are preferably provided with enlarged bases formed of elongated spaced-apart members 26 at their bottom and sides. Near the top of each of these supporting means is provided a spindle 27 for rotatably supporting the web roll by engagement with the ends of the axial orifice of the web roll and, as embodied, these 55 means preferably comprise a stub shaft 28 formed integrally at one end with an enlarged head or chuck 29, which can be tightly fitted into the ends of the axial orifice of the web roll 30. These engaging means, or 60 spindles 27, are rotatably supported in an enlarged cylindrical portion 31, 32 integral with the top of the support or pedestal 23 or 24, and are preferably mounted with ball bearings 33 to reduce the friction as much as 65 possible.

For preventing undesirable endwise movement of the shaft 28 in its bearings, there is preferably provided a sleeve 35, pinned to the shaft by pins 37, which sleeve extends between the inner races of the ball bearings 33. These 70 ball bearings are so formed that the two races prevent appreciable end-play and they are held in their seats, formed in the cylindrical heads 31, 32, by ring nuts 39.

Preferably, one of the spindles 27 is mounted 75 for endwise movement, so that it can be retracted a sufficient amount to allow a new web roll to be placed in the web roll supporting and handling mechanism, and means are also provided for locking this spindle against this endwise movement at other times and while the web roll is rotatably supported in running position. As shown in Figures 1, 3, 6 and 7, one of spindle shafts 28 is rotatably mounted in sleeve 40 by means of ball bearings 33, which together with sleeve 35, pinned to the spindle shaft 28, prevent endwise movement of the spindle relative to sleeve 40, the ball bearings being held in their seats by ring nuts 39. Sleeve 40 is slidably mounted in the cylindrical head portion 32 of pedestal 23 and held against rotative movement therein by key 41, slidably in key-way 42.

For moving spindle 27 and sleeve 40 in the head 32, and also for locking these parts against such movement, a toggle mechanism is provided, comprising a hand-lever 43 pivoted to a bracket 44 bolted on one side of sleeve 40 and within a slot in the side of head 32. With this cooperates a link 47, pivoted at one end 95 midway along lever 43 and at its other end to an anchor bar 45, slidable in a slot formed in head 32, and releasably secured in place by set screw 46. For locking the toggle, when a web roll is rotatably supported in running position and thereby preventing endwise movement of this spindle 27, a notched plate 48 is provided, rigidly secured to the bracket 44 and cooperating with a rod 49 slidable in guides 50 along lever 43 and moved into, and out of, engagement with the notches on plate 48 by movement of releasing lever 51. A spring between releasing lever 51 and lever 43 normally maintains the rod 49 in engagement with one of the notches to lock the toggle. An arm 52 extends from lever 43 and cooperates with stop pin 54 on link 44 to prevent excessive movement of the spindle, and the position of the spindle relative to its support may be varied by variably positioning anchor bar 100 105 45 in its slot.

Means are provided for temporarily receiving web rolls from the truck or other instrumentality on which they are brought up to the web handling and supporting mechanism and comprises a cradle onto which the web roll may be rolled and by which it is raised into position to be engaged by the spindles for rotatably supporting the web roll in running position. As embodied, the cradle 60 com- 110 115 120 125 130

prises side members 62 and end members 63 forming a hollow rectangular frame, fitting over the upstanding pedestals or supporting members 23, 24, and normally supported on and by the bed of the web roll supporting and handling mechanism. On each of the side members 62 are bolted a pair of arcuate-faced shoes 65 which support the new web roll and prevent its rolling off the cradle.

In the present illustrative embodiment, the cradle is vertically movable and held against endwise or sidewise movement by vertically-extending guides 66 at each side of the cradle ends, which guides engage with corresponding guideways cut in the end frames 63. Means are also provided for vertically moving the cradle to lift the web roll, temporarily received on the cradle, into engagement with the spindles and, as embodied, comprises a pair of cables 67, 68 at each end of the cradle adapted to be wound on or unwound from power-driven drums 69.

As here shown, a shaft 70, extending longitudinally and at one side of the bed of the web supporting and handling mechanism and journalled in brackets 72 at one side of the end frames 22 of the bed is connected with motor 74 by gear 75 and pinion 76. Drums 69 are mounted on shaft 70, and to these drums are fastened cables 67 and 68 which run over pulleys 77, 78, 79 and 80, 81, 82 respectively, and are fastened at their other ends near the corners of the cradle. Pulleys 77, 78, 80 and 81 are rotatably journalled in brackets formed integrally with the end frames 22 of the web roll supporting and handling mechanism, and pulleys 79 and 82 are journalled on stub shafts fastened to the outside of the end frames. As the motor 74 rotates in one direction the cables are wound on their respective drums and raise the cradle, and after the web roll has been engaged by the spindles, unwind to lower the cradle onto the bed of the mechanism in readiness to receive a new web roll when the new roll is to be placed in running position.

For accommodating web rolls of different widths, so that full-widths, three-quarter width, half-width, or quarter width webs can be fed to the printing press or other web-using mechanism as the necessities of the work may require, the supporting members or pedestals 23, 24 are slidably supported on the bed of the machine so the distance between these spaced-apart members can be varied as desired. For this purpose, alined, spaced-apart rollers 84 are journalled at each side of the base portion 26 of the supporting members and corresponding channel-like trackways 85 are cut on the inside of the side frame members 20 of the base of the web roll supporting and handling mechanism. The trackways and cooperating rollers give the bases of the pedestals greater rigidity and prevent any tilting of the pedestals which

might otherwise occur. Rollers 84 are preferably journalled on the pedestal bases by means of headed stub-shafts 86 held in place by nuts 87.

Means are provided for spacing the pedestal members apart and for preventing their movement along the bed of the web roll supporting mechanism, and comprise a threaded shaft 90, extending longitudinally and centrally of the base of the mechanism and rotatably journalled in the end frames 22 of the mechanism. Shaft 90 is held against endwise movement, with respect to the frame by means of collar 91 and gear 92, and the supporting members or pedestals are held against movement along the threaded shaft by means of threaded sleeves 94 engaging the threaded shaft 90, the threaded sleeves being centrally positioned at the bottom of the supports or pedestals 23 and 24.

For registering the web of paper or other material as it is paid off the web roll and with respect to the printing press or other web-using machine, means are provided for moving the supporting members 23, 24 and spindles 27 in unison and laterally of the web, whereby the web roll may be accurately moved to one side or the other and in the present instance, these means comprise a bevel gear 95 mounted on vertically extending shaft 96 journalled in brackets 97 extending from one of the end frames 22. Gear 95 meshes with the corresponding bevel gear 92 fixedly secured to the threaded shaft 90 and as hand wheel 98, secured to shaft 96, is turned, threaded shaft 90 is rotated causing a corresponding lateral movement of each of the pedestals or supporting members 23 and 24.

Means are also provided for disengaging the threaded sleeves at the bottoms of the pedestals or supporting members from the threaded shaft and for allowing the pedestals to be moved along the threaded shaft and for this purpose, the threaded sleeve is preferably formed in a plurality of separable sections so the sleeve can be expanded leaving the pedestals free to be moved toward or from each other. As embodied, each threaded sleeve 94 is formed as a split-nut, the two halves of which are formed, on their sides, with guide plates 99 and fitted between guides 100 formed in the base of the pedestals, as best shown in Figs. 8-11. Means are provided for holding the two halves of the threaded sleeve in engagement with the threaded shaft and for moving the sections apart, when desired, and comprise cam plates 102, at either end of the threaded sleeve and fitted over the threaded shaft 90, which plates are rotatably mounted by recessed guide plates 104 bolted on the pedestal base and over the cam plates 102. Cam plates 102 are provided with spiral cam slots 105 in which run small cam rollers 106 rotatably mounted

at each end of each of the sections of sleeves 94. As the plate 102 is turned, the cam slots cause the halves of the sleeve to be moved toward or away from each other and on the 5 guides 100.

For convenience in operation, there are preferably provided operating levers 108, pivoted on the upper portion of the pedestal or supporting members and connected with 10 arms 109, projecting from one side of the cam plates by links 110. As operating levers 108 are oscillated, cam plates are turned back and forth causing alternate opening and closing of the split sleeves.

15 Web tension controlling means are provided and in this embodiment comprise a brake mechanism operable on a spindle engaging one of the ends of the axial orifice of the rotatably mounted web roll. Preferably, 20 and as here shown, the brake mechanism is mounted on the spindle which is not longitudinally movable with respect to the pedestal or support on which it is mounted. A brake drum 115, fixed to the outer end of spindle 25 28 on pedestal or support 24, is provided with a deep V-shaped peripheral groove, with which cooperate corresponding arcuate brake shoes 117, of V-shaped cross-section, pivotally mounted on brake arms 118, 119, which in 30 turn are pivoted on shaft 120 outwardly extending from the head of pedestal 24.

The upper ends of the brake arms 118, 119 are yieldingly pressed together, to obtain the desired brake pressure for properly tensioning the web drawn off the web roll, by means of rod 121, pivoted in the upper end of brake arm 118 and passing through the upper end of the other brake arm 119. Hand wheel 122 threaded on the free end of rod 121 compresses spring 123 to force the brake shoes together and tension the web, which tension can be controlled as desired by movement of the hand wheel.

Assuming that a web roll has just been exhausted, the operations attendant the placing of a new web roll on the web roll supporting and handling mechanism are substantially as follows: If the web roll engaging spindles 27 are not spaced at a proper distance from 45 each other, the hand levers 108 are moved to separate the split sleeves 94 and permit the supporting members or pedestals 23 and 24 to be moved. These supporting members or pedestals are then moved apart by the operator and when positioned at the proper places, the hand levers 108 may be returned to their normal position to close the threaded sleeves on shaft 90 and hold the supporting members a fixed distance apart. When these 50 members have been properly adjusted, the longitudinally movable spindle 27 is retracted by movement of the hand lever 43, and a new web roll is rolled onto the cradle where it is supported by shoes 65. The operator 55 then closes the switch for motor 74 to raise

the cradle and the web roll and keeps the motor running until the axial orifice of the new web roll is in alignment with the spindles 27. After the web roll has been raised a sufficient distance in this manner, the motor is stopped, the hand lever 43 moved to jam the spindle chuck 29 into the axial orifice of the web roll and move the web roll onto the chuck at the other end of the axial orifice. The operator then allows the cradle to descend by gravity, or may reverse the motor to lower it, thereby completing the mounting of the web roll, on the supporting and handling mechanism and leaving it free to rotate. The leading end of the web from the new web roll is then joined onto the tail end of the exhausted web roll and the web is fed into the printing press or other web-using mechanism. If the web is not in register with the printing plates on the printing press cylinders, or with some corresponding part on the other web-using mechanism, the operator corrects this condition by turning hand wheel 98 to move the web roll laterally of the path of the web or towards one end of the mechanism, the threaded shaft 90 serving to keep the spindle supporting members uniformly spaced while moving them, and to lock the supports against further movement when the adjustment has been completed. The necessary tension on the web may then be established in the obvious manner, by the hand wheel 122 provided for varying the tension of the brake. While the several operations have been described in a particular order, it is apparent that most of them may be performed in any sequence and with the same effect as though performed in the order recited.

The invention in its broader aspects is not limited to the specific mechanisms shown and described but departures may be made therefrom within the scope of the accompanying claims without departing from the principles of the invention and without sacrificing its chief advantages.

What I claim is:—

1. A web roll supporting and handling mechanism including in combination means for engaging either end of the axial orifice of a web roll, threaded means for spacing and laterally moving said engaging means, a flexibly suspended cradle on which the web roll is received, and means for vertically moving said cradle to raise the web roll into running position.

2. A web roll supporting and handling mechanism including in combination means for engaging either end of the axial orifice of a web roll, threaded means for spacing and laterally moving said engaging means, a flexibly suspended cradle on which the web roll is received, and means for raising the cradle by its ends.

3. A web roll supporting and handling

- mechanism including in combination means for engaging either end of the axial orifice of a web roll, means for rotatably supporting said engaging means, threaded means engaging said supporting means for registering the web roll, and means for disengaging said supporting means from said threaded member for independent movement of said supporting means to accommodate web rolls of different widths. 70
4. A web roll supporting and handling mechanism including in combination means for engaging either end of the axial orifice of a web roll, means for rotatably supporting said engaging means, means for spacing and conjointly moving said supporting means to register the web roll, a cradle on which the web roll is received, and cables attached to said cradle, a common shaft on which the cables are wound for raising the cradle and a power means for turning said shaft. 75
5. A web roll supporting and handling mechanism including in combination means for engaging either end of the axial orifice of a web roll, means for rotatably supporting said engaging means, threaded means engaging said supporting means for registering the web roll, means for disengaging said supporting means from said threaded member for independent movement of said supporting means to accommodate web rolls of different widths, a cradle on which the web roll is received, cables attached to said cradle, a common shaft on which the cables are wound for raising the cradle, a power means for turning said shaft, means for moving one of the engaging means when changing web rolls, and means for retarding the rotation of the web roll. 80
6. A web roll supporting and handling mechanism including in combination means for engaging either end of the axial orifice of a web roll, means for rotatably supporting said engaging means, threaded means engaging said supporting means for registering the web roll, means for disengaging said supporting means from said threaded member for independent movement of said supporting means to accommodate web rolls of different widths, and means for moving one of the engaging means when changing web rolls. 85
7. A web roll supporting and handling mechanism including in combination means for engaging either end of the axial orifice of a web roll, means for spacing and laterally moving the engaging means, a cradle on which the web roll is received, cables attached to said cradle, a common shaft on which the cables are wound for raising the cradle and a power means for turning said shaft, and means for moving one of the engaging means when changing web rolls. 90
8. A web roll supporting and handling mechanism including in combination means for engaging either end of the axial orifice of a web roll, means for rotatably supporting said engaging means, threaded means engaging said supporting means for register- 95
- ing the web roll, means for disengaging said supporting means from said threaded member for independent movement of said supporting means to accommodate web rolls of different widths, a cradle on which the web roll is received, cables attached to said cradle, a common shaft on which the cables are wound for raising the cradle, a power means for turning said shaft, means for moving one of the engaging means when changing web rolls, and means for retarding the rotation of the web roll. 100
10. A web roll supporting and handling mechanism including in combination means for engaging either end of the axial orifice of a web roll, means for conjointly moving said engaging means for laterally registering the web roll, means for disengaging said engaging means from the moving means for spacing the engaging means for different widths of web rolls, and means for raising the web roll to bring the axial orifice into engagement with the engaging means. 105
11. A web roll supporting and handling mechanism including in combination means for engaging either end of the axial orifice of a web roll, means for conjointly moving said engaging means for laterally registering the web roll, and means for disengaging said engaging means from the moving means for spacing the engaging means for different widths of web rolls. 110
12. A web roll supporting and handling mechanism including in combination means for engaging either end of the axial orifice of a web roll, means for conjointly moving said engaging means for laterally registering the web roll, means for disengaging said engaging means from the moving means for spacing the engaging means for different widths of web rolls, means for raising the web roll to bring the axial orifice into engagement with the engaging means, and means for laterally moving one of said engaging means for positioning a new web roll. 115
13. A web roll supporting and handling mechanism including in combination means for engaging either end of the axial orifice of a web roll, means for rotatably supporting said engaging means, a threaded shaft 120
14. A web roll supporting and handling mechanism including in combination means for engaging either end of the axial orifice of a web roll, means for rotatably supporting said engaging means, a threaded shaft 125
15. A web roll supporting and handling mechanism including in combination means for engaging either end of the axial orifice of a web roll, means for rotatably supporting said engaging means, a threaded shaft 130

for moving and spacing said supporting means, split nuts on said supporting members and means for opening said nuts, whereby the supporting members may be moved to accommodate web rolls of different widths and to register the web laterally.

14. A web roll supporting and handling mechanism including in combination means for rotatably supporting either end of the

10 axial orifice of a web roll, a threaded member for spacing and laterally moving said supporting members and means for disengaging said supporting means from said threaded member whereby the supporting members

15 may be moved independently of each other.

16. A web roll supporting and handling mechanism including in combination spaced means for rotatably supporting a web roll, a threaded member for spacing said supports,

20 means for conjointly moving said supports along said member and means for disengaging said supports from said member whereby they may be independently moved along said member.

25 In testimony whereof, I have signed my name to this specification.

HUBERT LANG.
